Statement

UNITED STATES PATENT OFFICE.

ALBERT PELTZER, OF CHICAGO, ILLINOIS.

METHOD FOR CONSTRUCTING CONCRETE BUILDINGS.

1,066,436.

Specification of Letters Patent.

Patented July 1, 1913.

Application filed June 11, 1912. Serial No. 703,042.

To all whom it may concern:

Be it known that I, ALBERT PELTZER, a citizen of the United States, residing at Chicago, in the county of Cook and State of Illinois, have invented certain new and useful Improvements in Methods for Constructing Concrete Buildings, of which the following is a specification.

The present invention relates to certain new and useful improvements in methods of constructing buildings and the like from concrete and similar plastic material.

A primary object of the invention is to simplify and improve upon the manner of constructing concrete buildings, thereby both reducing the cost of construction and the time required for construction.

For a full understanding of the invention, reference is to be had to the following description and accompanying drawings, in which:

Figure 1 is a vertical sectional view through a portion of a concrete building which is in the course of construction, and is being constructed in accordance with the present invention. Fig. 2 is a partial plan view of one of the floor slabs. Fig. 3 is an enlarged sectional view through one of the floor lifting jacks, and Fig. 4 is a sectional view through a partially erected building, showing a modified form of the invention.

Corresponding and like parts are referred to in the following description and indicated in all the views of the drawings by the same reference characters.

In carrying out the invention, the ground floor and foundation are constructed in the usual manner, and the floor slab for the second floor formed directly on top of the ground floor slab. If desired, the floor slab for the third floor may be formed directly on top of the floor slab for the second floor and so on, suitable openings being left in the various floor slabs to receive the columns. Each lower floor slab thus forms a centering for the upper floor slab, and the various floor slabs can be quickly and inexpensively formed one upon the other without the use of the usual expensive molds. With a large building, it will be understood that each slab may be cut up into a number of independent units for convenience in handling, should such be found necessary or desirable. After one or more floor slabs have been formed on the lower or foundation floor slab, the said floor slabs are raised bodily and vertically

mounted upon the columns. After the lower floor slab has been raised to the required height it is suitably anchored upon the columns and the floor slab on top thereof then elevated to the required height. It will thus be seen that two or more slabs are molded on top of each other before raising any one of them, the said slabs being elevated and mounted in position after they have been allowed to set and harden.

One form of apparatus suitable for carrying out the method of construction is shown in Figs. 1, 2 and 3 of the drawing. The foundation 1 and lower floor slab 2 are molded or constructed in any suitable manner. The floor slabs 3, 4 and 5 for the second, third and fourth floors of the building are arranged over the ground floor slab 2. The floor slab 3 for the second floor is shown as having been raised and anchored in position upon the columns 6, while the floor slab 4 is partially raised and the floor slab 5 is shown as resting upon the floor slab 4. In forming each of the floor slabs 3, 4 and 5, suitable boxes or molds 7 would be placed upon the next lower floor slab so that the said lower floor slab would serve as a centering and support. These boxes or forms 7 may be of any desired type or style, although they are shown in the present instance as arranged to form a grid of intersecting reinforcing ribs, as shown more clearly by the dotted lines in Fig. 2. If desired, however, it will be understood that the floor slabs may be perfectly flat, or may be molded in any other suitable manner. The floor slab 3 for the second floor would be molded upon the ground floor slab 2 and would rest thereon in the same manner in which the upper floor slab 5 is shown as resting upon the floor slab 4, and in a similar manner the floor slab 4 would have been molded upon the floor slab 3. The forms 7 for the floor slab 4 are shown as still resting upon the floor slab 3, ready to be removed, and in a similar manner the form 7 for the upper floor slab 5 would be removed after the said slab had been elevated above the floor slab 4. The floor slabs are all formed with suitable openings 8 for the columns. After the floor slabs have been allowed to set and harden, reinforcing rods 9 for the columns are inserted in position, the said reinforcing rods passing through the floor slabs and being adapted to have the concrete molded about the same in the usual manner. In the

present instance there are six of these reinforcing rods 9 for each of the columns, and molds 10 are provided for enabling the columns to be formed as the floor slabs are raised.

A jack is provided for raising the floor slabs. This jack comprises an upper head 11 and a lower head 12 which are connected by an operating rod 13, the ends of the rod being formed with right and left hand threads respectively for engagement with the heads 11 and 12. These heads are each formed with the openings 14 through which the reinforcing rods 9 pass loosely, and also with laterally opening recesses 15 which intersect the openings 14 and receive the rod clamps 16. Each of these rod clamps is controlled by a screw 17, which is formed with an angular head. A casing 18 is applied to an intermediate portion of the operating rod 13 and carries a perforated eye 19 which loosely receives one of the rods 9, thereby holding the casing against rotation. A drive shaft 20 is journaled in a bearing 21 formed in one side of the casing 18, the said drive shaft being connected by gearing 22 to the rod. An angular head 23 is formed upon the outer end of the shaft 20, the said angular head being designed to engage a suitable handle for turning the shaft to operate the jack. The lower head 12 of the jack rests upon the upper floor slab and is provided with the hanger rods 24 passing through the slabs. Nuts 25 are threaded upon these hanger rods and engage the bearing plates 26 under the respective slabs.

In order to raise the floor slabs, the rod clamps 16 of the upper head 11 are tightened and the rod clamps 16 of the lower head 12 loosened. A suitable handle is then applied to the angular head 23 of the drive shaft and the said shaft rotated to turn the operating rod 13 and draw the two heads 11 and 12 toward each other. Since the upper head 11 has been anchored upon the reinforcing rods 9 by tightening the rod clamps 16, the lower head 12 of the jack will be raised and the floor slabs will be drawn upwardly with the same. The rod clamps 16 of the lower head 12 are then tightened to anchor the lower head 12 upon the reinforcing rods 9 and the rod clamps 16 of the upper head 11 loosened. The threaded operating rod 13 is then turned in the reverse direction to force the two heads 11 and 12 away from each other and move the upper head 11 upwardly on the reinforcing rods 9. The upper rod clamps 16 may then be again tightened and the lower rod clamps 16 again loosened, preparatory to repeating the first operation and again raising the floor slabs. The floor slabs may thus be raised step by step, until the required height is reached.

The molds 10 for the columns may be of any suitable construction and are provided with flaring mouths 10^a at their upper ends. These flared upper ends 10^a of the column molds are engaged by a casting or support 27 which has a threaded connection with hanger rods 28, the upper ends of the hanger rods being suitably connected to the bottom of the lower floor slab by means of suitable brackets 29. The distance between the lower floor slab and the column mold 10 can be regulated as may be desired, although the column mold 10 is rigidly connected with the lower floor slab so as to be raised with the same. The various floor slabs are provided adjacent the column openings with a second set of openings 30 through which a chute or spout 31 is inserted, the lower end of the spout being inclined laterally and designed to discharge into the flared upper end 75 of the column mold 10. As the floor slabs are raised, the brace or tie members 32 are applied to the reinforcing rods 9 for the column, and when the floor slabs have been raised a suitable distance, concrete is 80 poured through the chute 31 into the column mold 10 so as to form a concrete column for the support of the floor slabs. It will thus be obvious that the reinforced concrete columns are formed as the floor slabs are 85 raised. When the lowermost one of the floor slabs has reached the requisite height, a shoulder 6^a is formed upon each of the columns and the floor slab permitted to rest upon these shoulders. In Fig. 1 the floor slab 3 for the second floor is shown as having been raised the requisite height and as resting upon the shoulder 6^a. The remaining floor slabs may then be raised still further in the same manner, the columns being 90 formed as the floor slabs are raised, and the various floor slabs being anchored upon the columns by means of shoulders 6^a as soon as they have reached the requisite height. It will be obvious that all of the floor slabs 100 may be formed in successive layers, one upon the other, before any of the floor slabs are raised, or that fresh floor slabs made directly on top of floor slabs which have previously been raised, as may be found most desirable. 110

A modification is shown in Fig. 4, in which steel or cast iron columns are shown as employed. The foundation 1^a and ground floor 2^a are constructed as in the former instance, and the floor slabs 3^a, 4^a and 5^a are 115 also formed in substantially the same manner. The column receiving openings in the various floor slabs are somewhat larger than the diameter of the steel columns 33, in order to pass freely over the shoulders 120 formed by the flanges 34 at meeting ends of the column sections. The column receiving openings of the floor slabs are preferably reinforced by the thimbles or sleeves 35. 125

The lifting jack is very similar to that 130

previously described, and comprises an upper head 36 and a lower head 37, the said heads being connected by an operating rod 38 which has the opposite ends thereof provided with right and left hand threads respectively so that by turning the operating rods the heads 36 and 37 can either be drawn away or moved toward each other. These upper and lower heads 36 and 37 are formed with suitable openings loosely receiving the lifting rods 39, and are provided with rod clamps 40 adapted to engage the lifting rods. The lower ends of these lifting rods pass through the various floor slabs and are provided with nuts 41 engaging the flanged lower ends 35^a of the thimbles 35. A casing 42 surrounds the middle portion of the operating rod 38 and is provided with a perforated ear 43 receiving one of the lifting rods 39 to hold the casing against rotation. An operating shaft 44 is provided corresponding to the shaft 23 of the former jack, the said operating shaft being geared as in the previous instance to the operating rod.

In the operation of the jack, the lower head 37 thereof rests upon the upper end of the column, and the upper rod clamps 40 are tightened while the lower rod clamps 40 are loosened. The shaft 44 is then turned to operate the rod 38 and force the upper and lower heads 36 and 37 of the jack away from each other. The upper head 36 is thus moved upwardly and causes the floor slabs to be lifted owing to the fact that the upper rod clamps 40 are tightened, while the lower rod clamps 40 are loosened. The lower rod clamps 40 may then be tightened and the upper rod clamps 40 loosened preparatory to turning the operating rod 38 in a reverse direction and drawing the upper head 36 back to its original position. By again tightening the upper rod clamps 40 and loosening the lower rod clamps 40 the first operation may be repeated and the floor slabs raised another step. As soon as one of the floor slabs has

reached the required height, a bracket or shoulder 33^a is applied to the column 33 to support the floor slab and hold it in position. As in the present instance, this supporting collar 33^a may be shown as formed in two sections adapted to be applied to the column from opposite sides thereof and to rest upon one of the shoulders formed by the flanges of the column sections.

The essential feature of the invention resides in the method of constructing concrete buildings, whereby the floor slabs are formed or molded on top of each other and then subsequently raised, this manner of forming the floor slabs greatly decreasing the cost of construction, since each lower floor slab forms a casing for the upper floor slab.

Having thus described the invention, what I claim as new and desire to secure by Letters Patent, is:—

1. The method of constructing concrete buildings, which consists in first forming the floor slabs upon each other so that each lower floor slab forms a centering for the next upper floor slab, and subsequently raising the various floor slabs to the required height.

2. The method of constructing concrete buildings, which consists in forming a series of floor slabs one on top of the other, subsequently raising the floor slabs to the requisite height, and forming supporting columns as the floor slabs are lifted.

3. The method of constructing concrete buildings, which consists in forming a series of floor slabs one on top of the other, placing column members in position, raising the floor slabs upon the column members, and anchoring the various floor slabs at different heights upon the column members.

In testimony whereof I affix my signature in presence of two witnesses.

ALBERT PEITZER.
